UNITED STATES PATENT OFFICE.

SAMUEL MARTIN, OF PITTSBURG, PENNSYLVANIA, ASSIGNOR OF ONE-HALF TO WILLIAM T. JONES AND A. B. McVAY, OF PITTSBURG, PENNSYLVANIA.

BALANCED VALVE.

SPECIFICATION forming part of Letters Patent No. 722,733, dated March 17, 1903.

Application filed October 13, 1902. Serial No. 127,110. (No model.)

To all whom it may concern:

Be it known that I, SAMUEL MARTIN, a citizen of the United States, residing at Pittsburg, in the county of Allegheny and State of Pennsylvania, have invented certain new and useful Improvements in Balanced Valves, of which the following is a specification, reference being had therein to the accompanying drawings, forming part of this specification, in which—

Figure 1 is a partial longitudinal sectional view of an engine-cylinder provided with my improved balanced valve. Fig. 2 is a similar view showing the valve shifted to one side and registering with the inlet and exhaust ports, respectively. Fig. 3 is a horizontal sectional view of the valve-chest on the line III III of Fig. 1, the valve being shown in plan view partially broken away. Fig. 4 is a cross-sectional view on the line IV IV of Fig. 1. Fig. 5 is a cross-sectional view on the line V V of Fig. 3. Fig. 6 is a perspective view of the valve detached. Fig. 7 is a view similar to Fig. 1, showing a modified construction of valve. Fig. 8 is a similar view showing the valve shifted. Fig. 9 is a horizontal sectional view similar to Fig. 3. Fig. 10 is a cross-sectional view on the line X X of Fig. 8. Fig. 11 is a detached perspective view of the valve. My invention refers to the class of balanced valves wherein means are provided for relieving or counteracting the friction due to steam-pressure and tending to hold the valve to its seat. It is well understood that such pressure renders the operation of valves, especially with large sizes, very difficult, and my invention is designed to overcome such difficulty, as well as to contribute to the general efficiency of the valve.

My improvement consists in the construction of the valve itself, whereby a measured quantity of steam is supplied to the port at each operation; to the delivery-port thereto; the circulation-port for providing a counter-pressure; the regulating-valve for governing the supply, and other details of construction, which shall be more fully hereinafter set forth.

Referring now to the drawings, 2 is the usual cylinder, provided with inlet-ports 3 and

and exhaust-port 4, communicating with the 50 interior of steam-chest 5.

6 is the slide-valve, mounted in the interior of the steam-chest, actuated in conformity with the movement of the engine-piston by valve-rod 7 and suitable eccentric or other 55 gearing. Valve clearance-space is provided at each end of the valve, which space is also utilized in the open-ended construction of Sheet 2 for circulation to the engine-ports. The interior of valve 6 is hollow, and it may 60 be closed by a surrounding wall and provided on its under face with ports 8 and exhaust-port 9, adapted to establish communication with ports 3 and 4 of the cylinder, as on Sheet 1, or it may be provided with end openings 21, 65 through which the steam escapes to the interior of the valve-chamber at each end and thence to the ports 3 when uncovered, as on Sheet 2.

At one end the valve is provided with an 70 inlet-port 10, adapted to register in the middle position of the valve, as in Figs. 1 and 7, with an inlet supply-port 11 in the end wall of the valve-chamber, to which the steam is supplied by any suitable connection. In the 75 upper portion of the valve is a transverse port 12 of sufficient width to always register with supply-port 11 in all positions of the valve, the purpose of which port is to supply steam-pressure against the other end of the 80 valve, thus equalizing the pressure against the closed portion of the inlet end. For the purpose of confining the steam at such other end to the area of the valve 6 alone and preventing it from escaping to the interior I employ a pressure-plate 13, recessed at 14 on the interior for a portion equivalent to the counteracting pressure area desired and having a surrounding bearing-surface adapted to make a tight fit against the end of the 90 valve. Temper-screws 15 bear against cushion-springs 16, which in turn bear against the plate, so that the plate may be delicately adjusted against the valve without unnecessary rigidity.

Mounted in a suitable bearing 17 in the valve-chest is a throttle-valve 18, provided with a port 19, adapted to register with inlet-

port 11 and with the supply-opening 20 and by which the volume of steam admitted to the valve-chest inlet-port may be accurately regulated according to the load. I have found 5 considerable advantage in thus locating the throttling-valve and incorporating it with the valve-chest, resulting in great compactness of construction and convenience of manipulation.

10 In operation a charge of steam is admitted to the hollow valve at its middle position, the ports 10 and 11 being in register and both ports 3 being closed, as in Fig. 1. Movement of the valve toward either end will close 15 ports 10 11 and uncover one of ports 3, placing it either in register with the closed interior through one of the ports 8 or with the interior of the valve-chamber through open end 21, Fig. 8, into which the charge of steam 20 under pressure has been delivered and from which it will then pass through one of ports 3 to one end of the cylinder before a new charge is again admitted. By this construction and operation it will be seen that upon 25 the escape of steam through ports 3 pressure upon any of the exterior surfaces of valve 6 will be relieved and any binding or frictional pressure will be reduced to a minimum, further supply of steam being cut off until port 30 10 of the valve is again in register with port 11. In the closed construction of valve there is no escape of steam to the surrounding interior of the valve-chamber and no communication except through ports 8 or ends 21 to 35 ports 3, while in both constructions the charge of steam is cut off from the main supply and no more steam admitted until such charge is delivered to the cylinder.

The construction is very simple and not 40 liable to get out of order, while the advantages of the invention will be appreciated by all those familiar with this class of mechanism and the ease of operation of the valve is greatly increased.

45 Having described my invention, what I claim is—

1. A slide-valve having a hollow interior and an inlet-port adapted to register with a supply-port at the middle position of the 50 valve only, substantially as set forth.

2. A slide-valve having a hollow interior and an inlet-port adapted to register with a supply-port and a transverse pressure-supply port, extending laterally at each side 55 beyond the inlet-port, substantially as set forth.

3. A slide-valve having a hollow interior and an inlet-port adapted to register with a supply-port at the middle position of the

valve only, and delivery-ports adapted to 60 register with the inlet-ports of a cylinder, substantially as set forth.

4. The combination with a valve-chest provided with an inlet-port, of a hollow valve provided with a port adapted to register 65 therewith at its middle position, and to cut off the supply therefrom upon movement in either direction, substantially as set forth.

5. The combination with a valve-chest provided with an inlet-port and a controlling- 70 valve, of a hollow valve provided with a port adapted to register therewith at its middle position, and to cut off the supply therefrom upon movement in either direction, substantially as set forth.

6. The combination with a valve-chest provided with an inlet-port, of a hollow valve provided with a port adapted to register therewith at its middle position, and provided with ports adapted to register with cylinder-ports, substantially as set forth. 75

7. The combination with a valve-chest provided with an inlet-port, and a pressure-plate at the opposite side, of a hollow valve provided with a supply-port, and a separate 80 pressure-port, adapted to register with the inlet-port, substantially as set forth.

8. The combination with a valve-chest provided with an inlet-port, and a pressure-plate at the opposite side, of a hollow valve provided with a supply-port, adapted to register therewith at the middle position of the valve 90 only, and a separate pressure-port adapted to register with said inlet-port at all positions of the valve, substantially as set forth. 95

9. The combination with a steam-cylinder and a valve-chest provided with an inlet-port and ports leading to each end of the cylinder respectively, of a hollow valve having inclosing walls, a port adapted to register with the inlet-port, and ports adapted to register with the cylinder-ports respectively, substantially as set forth. 100

10. The combination with a steam-cylinder and a valve-chest provided with an inlet-port and ports leading to each end of the cylinder respectively, of a hollow valve having inclosing walls, a port adapted to register with the inlet-port, and ports adapted to register with the cylinder-ports respectively, and a separate 105 transverse pressure-port, substantially as set forth.

In testimony whereof I affix my signature in presence of two witnesses.

SAMUEL MARTIN.
